ATTORNEY

UNITED STATES PATENT OFFICE.

ALBERT O. TROSTEL, OF MILWAUKEE, WISCONSIN.

BALL.

Original application filed June 12, 1922, Serial No. 567,877. Divided and this application filed July 25, 1923. Serial No. 653,621.

To all whom it may concern:

Be it known that I, ALBERT O. TROSTEL, a citizen of the United States, residing in the city of Milwaukee, county of Milwaukee, and State of Wisconsin, have invented a certain new and useful Improvement in Balls, of which the following is a specification.

The invention relates to playing balls and more particularly to baseballs.

The object of the invention is to produce a baseball in which the entire body, when a cover is used, or the entire ball without a cover, is made of compressed felted keratoid material which retains its shape and resiliency under hard usage and which requires no windings to keep it in shape.

A further object of the invention is to provide a baseball which answers association requirements, which is much simpler in construction than the usual baseball and may be produced at a low cost.

In the drawings: Fig. 1 is a vertical sectional view through a ball embodying the invention; Fig. 2 is a vertical sectional view through a ball similar to Fig. 1 and provided with a cover.

Referring to the drawings, the numeral

3 in Fig. 1 designates the ball constructed of compressed felted keratoid material or 30 felted hair. In this instance the felted hair forms the entire body and is compressed to its finished spherical form. In Fig. 2 the compressed felted keratoid material, as shown in Fig. 1, is provided with an outside covering 4. This covering 4 is not necessary to keep the shape of the ball but is required on regulation baseballs.

The preferred manner of forming the baseball from the felted keratoid material 40 is more particularly described in my pending application, Serial No. 567,877, filed June 12, 1922, of which this application is a division.

What I claim as my invention is:

1. A ball having its body composed entirely of compressed homogeneous felted keratoid material.
2. A baseball in which the entire body of the ball is composed of felted hair compressed to finished spherical form.
3. A baseball in which the entire body of the ball is composed of felted hair compressed to finished spherical form, and an outside covering for said body.

ALBERT O. TROSTEL.
